Specification of Letters Patent.

Patented Sept. 2, 1913.

Original application filed May 23, 1908, Serial No. 434,702. Divided and this application filed July 25, 1910. Serial No. 573,683.

To all whom it may concern:

Be it known that we, FREDERICK BAKER and LESSER JACOBS, both subjects of the King of Great Britain, residing, respectively, 5 at 42 Lee road, Blackheath, in the county of Kent, England, and 17 Hanover Square, in the county of London, England, have invented a certain new and useful Seam for Sewed Articles, being a division of an application filed by us on May 23, 1908, Serial No. 434,702, since become Patent No. 10 1,014,033, of which the following is a specification.

This invention relates to an improved 15 novel type of stitching, the chief object being to enable a locked or fast stitch to be produced with the employment of a single thread, thus dispensing with the use of a shuttle or bobbin carrier.

20 According to the present invention the method of sewing consists in drawing out a loop of thread from the needle after the latter has penetrated the material to be sewn, releasing it when drawn out, causing 25 it when being drawn up to be arrested and retained by a tension device, drawing out one or more other loops in succession from the needle, passing them, (if more than one), in succession over the bight of the 30 first loop to embrace it at intermediate points in its length, drawing them up in succession so that they lock the first loop to the material, drawing out another loop through the bight of the first loop, and 35 liberating the said first loop from the tension device. The loop that has just passed through the bight of the first loop is then retained in tension and the sequence of operations is repeated. In this way there is 40 obtained a type of stitching consisting of a series of interlinked loops, which may be termed main loops, each of which is embraced by and locked to one or more loops termed sub-loops. The sub-loops which are 45 drawn through the main loop before being made to embrace it, not only embrace the main loop but are themselves embraced by it, and thereby result in the formation of a knotted stitch. Each main loop after being 50 drawn out is released, and in being drawn up is arrested by the above mentioned tension device at a certain point, the distance of which from the usual needle hole determines the length of the main loop.

The arresting member of the device moves 55 forward step by step as the feeding forward of the material takes place with the result that uniformly spaced stitches can be produced. The means employed for producing stitches of this character comprise a movable loop catcher or hook which may conveniently form part of or be mounted upon a disk, and the tension device, which is situated at one side of the path of movement of the said loop catcher or hook. 60 The loop catcher or hook engages with the needle thread at each descent of the usual reciprocating needle, and after drawing out a loop of thread, releases the said loop in such a position that when being drawn up 65 it passes over the surface of the aforesaid tension device. This device contains the before mentioned arresting member for arresting and yieldingly holding a loop in tension but allowing one or more succeeding 70 loops to pass completely over it before it releases the loop it has been retaining; each retained loop becomes a main loop, and each unretained loop becomes a sub-loop. It may here be pointed out that each sub-loop 75 constitutes a stitch, and also each point of interlinkage of the main loops, and that each stitch is completed before the formation of the next stitch begins.

In order that the invention may be clearly 85 understood and readily carried into effect, the same will now be described more fully with reference to the accompanying drawings which illustrate the stitches, and, by way of example, one construction of machine for carrying out the invention.

Figure 1 is a side elevation, and Fig. 2 a plan view from underneath, of two pieces of material sewn by our knotted type of stitching. The thread is of course only 95 shown diagrammatically, the stitching being much enlarged and drawn up only very loosely. Fig. 3 is an elevation of part of a machine constructed for producing stitching in accordance with this invention. Fig. 4 is an enlarged side elevation of the tension device seen in Fig. 3. Fig. 5 is a 100 face view showing the needle thread in the act of being engaged preparatory to the drawing out of a loop by the loop catcher or hook on the disk. Fig. 6 shows the disk advanced to a position where the loop has been drawn out and the hook tilted to

disengage the loop therefrom and transfer it to the lower end of the tension device ready to be drawn up over the back of the same. Figs. 7, 7^a and 7^b illustrate a modified form of tension device hereinafter described.

A is the needle, B the usual needle plate, C the needle thread, D the disk carrying the loop catcher or hook d^x, and E the tension device. The disk D is preferably formed in one piece with its driving spindle or shaft. The hook d^x forms part of a pivoted member d' adapted to be rocked on a pivot d² by a toothed quadrant d³, the teeth of which engage with teeth on one end of the member d'. Carried on the quadrant d³ is a cam like projection d⁴ adapted during a revolution of the disk to engage with projections d⁵ d⁶ depending from a bridge piece 10 G carried by the bearing plate H, in such a manner that upon meeting the projection d⁵, the hooked end of the member d' is thrown outward, while the meeting with the projection d⁶ imparts motion to the 15 hooked member again, in the opposite direction. The purpose of these movements will be apparent later on in the description.

At the back of the disk are cam grooves d⁸ and d⁹ and pins fixed to sliding members 20 d^{8x} d^{9x} are arranged to work in the aforesaid grooves as the disk D rotates. The sliding members d^{8x} d^{9x} extend beyond the periphery of the disk and beyond the casing e of the tension device E and have lateral projections d¹⁰ and d¹¹ which extend over the back 25 face of the said casing and make contact with it to hold it in position on the periphery of the disk, which is grooved to accommodate a projecting rib on said tension device casing and thereby prevent lateral 30 movement of the latter. In order to prevent any loose or uncertain action of the projection d¹⁰ that might otherwise occur owing to the wearing of the walls of the 35 groove d⁸ and of the pin on the sliding member d^{8x}, a spring d^{10xx} may be provided to constantly press the said pin against the inner edge of the groove.

The tension device casing, shown on a 40 large scale in Fig. 4, is equipped with a rocking member e' provided with a hook e² and controlled by a spring e³, the casing e being slotted to expose the hook e². The rocking member e' carries a pin or projection e⁴ which is normally engaged by a pivoted arm e⁵ to prevent the rocking of the member e'. The member e' is however released during a certain part of the revolution of the disk D by the lug d thereon in 45 the manner to be hereinafter described. The mechanism for feeding the material forward step by step is of the well known kind.

As soon as the needle descends through 50 the material to be sewn, the hook d^x on

the member d', which is at this point in its inward position, engages the thread (Fig. 5) and carries it around as it proceeds on its revolution, the sides of the loop falling one on each side of the disk and tension device, until the projection d⁴ comes into contact with the projection d⁵ on the bridge piece G (Fig. 6). This contact causes the member d' to assume its outward position and allows the loop of thread to 55 escape from the hook d^x. It is to be noted that this release of the loop has taken place before the hook has moved through 180° from its point of engagement with the thread. Consequently the loop when 60 drawn up passes along the same side of the axis of the disk as that on which it was drawn out instead of on the other side of this axis as is the case in prior rotary disk machines. The loop of thread is now pulled 65 by the usual take up back over the tension device, the retaining sliding pieces d¹⁰ and d¹¹ being operated successively by the cam grooves d⁸ and d⁹ at this moment, in order 70 to allow the thread to pass between them 75 and the tension device casing e. The loop is then arrested by the hook e² on the rocking member e' and held taut. The loop cannot avoid entering the hook e² owing to the guide e^x on the underside of the needle plate 80 B. As the disk continues its rotation, the lug d comes into contact with a projection e^{5x}, on the arm e⁵, causing it to lift clear of the pin e⁴ and allowing the member e' to 85 move forward step by step as the material 90 is fed onward. The member d⁴ also comes into contact with the projection d⁶ which 95 brings the member d' inward, and a guide bar d^x, as shown in Fig. 3, prevents its 100 tendency to fly outward on its upward journey before engaging the thread and beginning its downward course. The needle is 105 by this time descending again and in doing so, passes down between the sides of the retained loop, which is a main loop of definite 110 length. The thread is again caught by the hook d^x, and a second loop is drawn and carried around to the lower end of the tension device and then thrown off as before.

Owing to the hook e² having been released as above described and drawn away from the guide e^x by the forward movement of the material, this second loop, which forms a sub-loop, in being drawn over the tension device casing escapes the hook e² and therefore passes over the main loop which is still being held by the hook e², and is drawn taut against the material forming a knot with the main loop firmly locking it at one portion against the material. On the next descent 115 of the needle it passes again through the remaining portion of the main loop and a sub-loop is again passed over it as just 120 previously described, the main loop again moving a step forward owing to the feeding 125 130

of the material. This last step forward of the main loop, causes it to overcome the tension of the spring e^3 and escape from the hook e^2 , after which it is arrested by the upward projection e^6 secured to the end of the casing e . In this position, the bight of the loop is ready for the needle to pass through it. As soon as the loop escapes from the hook e^2 , the member e' springs back to its normal position, the pin e^4 engaging with the pivoted arm e^5 and securely retaining the member e' in its locked position. On the next descent of the needle, it passes through the bight of the main loop, which is held as above stated, and a new main loop is drawn off and caught on the hook e^2 , as in the original formation of the old main loop but it has been drawn through the bight of the old main loop. As the new main loop is pulled taut on the hook e^2 , it lifts the bight of the old main loop clear of the upward projection e^6 , which returns to its normal position. The bight of the old main loop is thus secured by the new main loop which is again locked in two places as before.

When the needle descends through the bight of the old main loop it is desirable that it should do so as close as possible to the end of the bight so as to produce a neat stitch. To enable the needle to descend as described, the needle plate is recessed to allow the tension device casing to be placed in such a position as to cause the bight of the loop, just prior to its release, to be placed close against the underside of the material and in position for the needle to enter it when it descends.

A modified form of tension device is shown in Figs. 7, 7^a and 7^b. In this arrangement, the member h , which corresponds to the member e' of Fig. 4, carries a hook e^{20} pivoted thereon at h' and is arranged to slide in a segmental groove in the casing or body portion h^3 , being retained in said groove by a plate h^4 . A spring h^8 , attached at one end to the casing h^3 and at the other end to a pin on the sliding member h , serves to pull the said member h into a position in which a lug or tail piece h^5 on the hook e^{20} catches against the stationary pin h^7 on the casing or body portion h^3 . The hook e^{20} is then, as shown in Fig. 7, projecting beyond the casing or body portion h^3 through an opening in it and is ready to catch a main loop of thread.

d^{10} and d^{11} are the projections operating similarly to those already described with reference to Fig. 3, with the exception that while the projection d^{11} engages with the casing or body portion h^3 only, the projection d^{10} projects through the latter, and engages with a notch h^9 on the member h . When therefore a main loop of thread has been caught by the hook e^{20} , the projection d^{10} prevents the member h from moving while the thread of the main loop is being

drawn by the take-up. Prior however, to the next loop, which is the first sub-loop, being drawn over the casing or body portion, the projection d^{10} is temporarily retracted as hereinbefore described, and owing to the feeding mechanism having now caused a tension to be exerted on the hook e^{20} by the thread, the sliding member h slides to the left toward the needle against the influence of the spring h^8 . The lug or tail piece h^5 then moves away from the pin h^7 and assumes a more horizontal attitude in which position the hook e^{20} lies below the top edge of the casing or body portion h^3 and therefore allows the sub-loop to pass over it. The next sub-loop also passes over the hook, the latter being drawn stitch by stitch to the left in opposition to the action of the spring h^8 until it has reached a position in which the lug h^5 approaches the periphery of the disk D as shown in Fig. 7^a. A projection, such as the lug d (Fig. 3), then engages with the end of the lug h^5 as the disk rotates and thereby tilts the said lug h^5 ; the hook e^{20} is consequently rocked sufficiently to release the loop. The hook e^{20} and sliding member h are then returned by the spring h^8 to their normal position and the hook e^{20} is then ready to engage with another main loop.

The hook e^{20} is pivoted on a pin in the sliding member h in such a way that it can slide laterally on the pin. A spring e^{xx} is secured to the sliding member h and its free end reaches over the aforesaid pin on one or other side of the pivoted hook e^{20} . In the position shown in Fig. 7^b a main loop when caught and held by the hook e^{20} will be kept to one side of the needle with the result that the sub-loops are drawn down to one side of the main loop. The hook e^{20} , however, finally moves up close enough to the path of the needle for the latter to pass through the bight of the old main loop in forming the new main loop.

What we claim and desire to secure by Letters Patent of the United States is:—

1. A seam comprising puncturable material, and a single thread bearing on one side of the material and having a series of main loops and sub-loops drawn through the material from the said thread, each main loop being of a predetermined length and bearing upon the other side of the material with its bight interlocked with the next main loop and its intermediate part embraced by and embracing a sub-loop which thereby locks it to the material.

2. A seam comprising two or more pieces of material and a line of stitching formed by a single thread having a series of main loops and sub-loops therein drawn through the material, the main loops being connected with one another by a chain-stitch, and the sub-loops each locked by a knotted stitch to one of the main loops.

3. A seam for uniting puncturable material with a single thread comprising a thread which passes through said material and extends in a relatively long main loop
5 in the line of the seam, a plurality of relatively shorter sub-loops which pass through the relatively long main loop and then around said main loop to embrace it at intermediate points in its length and about
10 which said sub-loops are drawn to lock

them to the main loop, and a second relatively long main loop passing through the bight of the first long main loop.

In testimony whereof we affix our signatures in presence of two witnesses.

FREDERICK BAKER.
LESSER JACOBS.
